FIRE EXTINGUISHER

Roscoe C. Iddings, Dayton, Ohio, assignor to The Fyr-Fyter Company, Dayton, Ohio, a corporation of Ohio

Application June 17, 1929. Serial No. 371,379

8 Claims. (Cl. 169—32)

This invention relates to fire extinguishers, and particularly to fire extinguishers of the chemical reaction type.

One of the principal objects of this invention is to provide a fire extinguisher mechanism of this type which is simple and sturdy in construction, has long life, is effective and reliable in operation, is capable of receiving a charge of highly reactive chemicals and provides for a controlled limiting of the rate of discharge and mixing of the chemicals upon use of the mechanism to secure an effective and desired pressure generation.

Other objects and advantages of this invention will be apparent from the following description, the accompanying drawing and appended claims.

In the drawing, in which like characters of reference designate like parts throughout the several views thereof—

Fig. 1 is a central vertical sectional view of an extinguisher constructed in accordance with this invention; and

Fig. 2 is an enlarged partial vertical sectional view illustrating the position of parts in inverted position of the extinguisher.

While the fire extinguisher herein described will satisfactorily operate upon a variety of charge materials, it is adapted particularly to receive a highly reactive charge comprising a relatively concentrated carbonate solution such as potassium carbonate within the outer container, and an acid such as chlorosulphonic acid within the inner container. The present extinguisher is constructed to effect such a controlled limiting of the rate of discharge of acid and mixing of the chemicals upon inversion of the extinguisher as to cause the pressure to rise slowly and to be maintained throughout a greater portion of the period of discharge, as is required by Underwriters' Laboratories.

Referring to the drawing, the extinguisher comprises a sheet metal container 10, preferably of sheet copper tinned on the inside, having a portion 11 with a flat face which serves as a base on which the container may set when not in use. The lower end of the container is closed by a sheet metal bottom 12 which may be fastened to the wall of the outer shell in any suitable manner such as by soldering. The top of the shell is provided with a centrally arranged opening which receives therein a cover casting 14, preferably copper, to which this end of the shell is soldered. The upper end of the cover casting is threaded to receive thereon a cover member 15 carrying a suitable handle 16, which as shown is in the form

of a ring to serve as a base upon which the extinguisher is adapted to rest when inverted. An annular washer 17 is positioned between the cover 15 and the upper end of the cover casting 14.

Adjacent the upper end of the extinguisher, and passing through the wall of the extinguisher shell is a discharge casting 20. This casting is provided with an enlarged shoulder 21 which is soldered to the shell. Attached to the inner end of the casting 20 is a flaring sheet metal member 22 receiving a screen 23, and the outer end of the casting is provided with a threaded nipple 24 which receives the usual flexible hose 25 carrying a discharge nozzle 26.

When an acid such as chlorosulphonic acid is used, it is preferable to provide a hermetically sealed acid container to prevent fuming and corrosion. In order to insure proper operation of the extinguisher upon inversion when such a sealed acid container is used, the inner container

is provided with a frangible closure, and means are provided for breaking the frangible closure upon inversion. As shown, the upper end of the inner face of the cover casting 14 is offset to provide a shoulder 30 upon which an annular

ring member 31 rests. The member 31 is provided with a downwardly depending skirt portion 32, and the lower end of this skirt portion is formed with inwardly extending arms 33 connected at their inner ends to a cylindrical mem-

ber 34, the parts 31, 32, 33 and 34 preferably being formed in an integral casting. The cylindrical member 34 is open at top and bottom and receives therein a sheet metal tube 35, the tube being rigidly connected to the ring 34 such as

by soldering. The tube preferably extends throughout a substantial portion of the length of the extinguisher and its lower end is closed by a bottom casting 36. This casting may be formed with an annular groove 37 within which

the lower end of the tube 35 seats and is soldered thereto. The upper end of the tube 35 terminates above the cylindrical member 34 and in spaced relation to the cover 15, thus opening above the

normal liquid level within the outer container 10.

Resting within the tube 35 is a hermetically sealed acid bottle 40. This bottle preferably seats upon a coiled spring 41, the lower end of which is positioned beneath an upper flange 42 of the bottom casting 36 to prevent the spring

from being displaced from the tube 35 upon removal of the parts for cleaning. The spring 41 permits the acid bottle to be dropped to the bottom of the tube when a fresh charge is being

provided without danger of breaking. Carried

110

by the cover 15 in alignment with the tube 35 is a pointed projection 45, this projection being shown as having an upper end 46 of smaller diameter pressed within an inwardly opening bore formed within a central boss 47 of the cover 15. In order to facilitate the sliding of the acid container 40 upon inversion of the extinguisher, the tube 35 is preferably provided with interiorly extending ribs 48, which may be rolled in the sheet metal. A cross pin 49 is pressed or otherwise secured within a transverse bore within the projection 45 in order to limit the descent of the container 40 to hold the end thereof in spaced relation to the cover to permit the proper feed of acid from the container after breaking.

The inner container 40 may be constructed as shown more clearly in Fig. 2 with a relatively thick glass body portion 50 and contracted neck portion 51. In order to hermetically seal the acid bottle, the end is blown in the form of a bulb 52 having a relatively thin walled frangible upper portion 53. This construction insures the shattering of the thin frangible portion 53 without danger of the complete shattering of the acid bottle which would permit the contents thereof to be suddenly introduced into the liquid within the outer container to give an unduly rapid and dangerous pressure rise.

It is found that when using a charge of a solution containing per unit volume large quantities of carbonate, and an acid such as chlorosulphonic acid, the initial reaction of the chemicals is very violent, and the gas pressure tends to build up too rapidly when the conventional extinguisher constructions are used. In accordance with this invention, means are provided for effecting a controlled limiting of the rate of discharge of acid from the inner container 40. This may be accomplished by forming the contracted neck portion 51 of the bottle 40 of a predetermined size which is coordinated with the effective cross section of the breaking projection 45. It is found however in commercial manufacture and production that it is difficult to form different bottles 40 with uniform neck portions 51, so that varying flow areas may result with different bottles, and produce different operating characteristics with varying pressure curves.

The present invention provides an extinguisher which is uniform in operation and which at the same time is simple and cheap in construction and wherein the necessity of accurate manufacture of the glass portion of the bottle 40 is avoided. This is accomplished by the provision of a metal metering or cap member 55, which as shown may be formed as a metal casting. The casting is preferably made of acid resistant metal, very satisfactory results being secured with a lead antimony alloy consisting of approximately 95% lead and 5% antimony. This metal member may be fastened to the glass bottle in any suitable manner. As shown, the metal member is provided with a depending skirt 56 which surrounds the end or neck portion 51, the lower end of the skirt 56 seating upon the upper end of the body portion 50 of the bottle. The member 55 is preferably fastened to the bottle by means of a plastic cement such as a mixture of sodium silicate and china clay, plaster of Paris, or a mixture of litharge and glycerin. A cement composed of a mixture of sodium silicate and china clay is preferred for this purpose as it remains plastic for longer periods, is easier to handle, and is quite resistant to acid.

75. In forming the charge holding container or

bottle 40 with acid charge therein, the bottle is blown generally in the shape shown with a neck portion 51 and a bulbous portion 52, an opening being left in the top of the bulbous portion 52 through which the acid charge is supplied to the container. The bottle is then hermetically sealed as indicated at 54. A quantity of plastic cement is then placed about this neck and bulbous portion of the bottle, or within the depending skirt 56 of the metal member 55, or both, and the end of the bottle inserted within the hollow cylindrical skirt 56 to the desired position. The excess cement is then scraped off, and the bottle laid aside to permit the cement to set to firmly attach the metal metering member over the frangible end of the bottle. To more securely attach the metering member 55, the inner surface of the depending skirt 56 is preferably provided with an irregular surface, such as a groove 58, within which the cement is pressed during assembly to provide a locking engagement.

The upper end of the member 55 is formed with a thickened portion indicated at 60, thereby providing a relatively large mass of metal which affords sufficient weight to insure rapid sliding movement of the bottle 40 upon inversion of the extinguisher to cause breaking of the frangible portion thereof. The upper surface of the member 55 is formed with an inclined guiding portion 61 which terminates in a constricted orifice 62 of predetermined size in alignment with the frangible portion 53 of the bottle. In this manner, a uniform metering orifice 62 of predetermined cross-section is provided which does not appreciably vary in commercial production for different castings. If desired, the metering orifice 62 may be drilled and the inclined portion formed with a countersink, but generally satisfactory results are obtained by casting the metal member in the form shown.

In operation, when it is desired to use the extinguisher the container 10 is inverted. This results in a sliding movement of the bottle 40 along the ribbed tube 35. The diameter of the bottle and the exterior diameter of the member 55 is preferably somewhat less than the interior diameter of the circle passing through the inner extremities of the ribs 48 whereby the bottle has only a limited surface engagement with the ribs. This construction in conjunction with the weighted end 60 of the bottle insures a rapid sliding movement along the tube 35. The ribs 48 serve to guide the bottle 40 in its sliding movement to properly maintain the same sufficiently centered so that the point of the projection 45 enters the larger opening formed by the inclined surface 61 which guides the point into the orifice 62 of the metering member. Due to the force of the sliding bottle and the thin-walled construction of the frangible portion 53, the point shatters the thin frangible end 53 so that the portion of the glass back of the orifice 62 is removed so that the orifice 62 then becomes the metering orifice. The bottle is so constructed that the interior diameter of the neck 51 is larger than the diameter of the orifice 62. After the pointed projection 45 has broken the frangible closure of the bottle, the bottle continues to slide down about the projection until as shown in Fig. 2 the metering member 55 comes into engagement with the cross pin 49. In this feeding position the projection 45 extends within the orifice 62. The size of the projection 45 is co-ordinated with the size of the orifice 62 to form

- an annular constricted channel 64 therebetween which effects a controlled limiting of the flow of acid from the bottle to give a predetermined rate of discharge. 80
- 6 When the extinguisher is inverted, the liquid within the outer container rushes downwardly and into the annular channel 65 formed between the depending skirt 32 and the cylindrical member 34 and between this member and the end of the tube 35. The tubular member 32 is of a size to surround the upper end of the tube and related parts in such spaced relation as to provide an annular channel 65 of predetermined restricted size, serving to effect controlling limiting of the rate of mixing of the chemicals. A port 68 of predetermined restricted size is formed in the side wall of the tubular member 32, or a plurality of restricted ports. The effective opening of the port, or combined area of the plurality of ports, is restricted so that the controlled limiting of the rate of reaction as above described is effected. This construction permits a controlled and restricted flow of the solution within the outer container through the ports 68 and/or 95 through the channel 65 into the space 66 of the initial reaction zone, while gas generated by the reaction in the space 66 may pass upwardly through channel 65 and/or the ports 68 to provide the expelling gas pressure within the outer container. The provision of the port or ports 68 is found to give good operating characteristics in a device of this character with an even pressure rise without markedly irregular gas ebullition from the reaction space 66. It is believed 100 that this may be due to the fact that by permitting some liquid to flow into the reaction space 66 through the port or ports 68 due to the hydrostatic head of liquid and gas pressure above the liquid, the gas is permitted to more readily escape 105 from the reaction space in an upward direction through the channel 65. In any event with this construction, the expelling gas pressure rises at a controlled and safe rate, and effective gas pressure is maintained throughout a greater portion 110 of the period of discharge. 115
- While the form of apparatus herein described constitutes a preferred embodiment of the invention, it is to be understood that the invention is not to be limited to this precise form, and 120 that changes may be made therein without departing from the scope of the invention which is defined in the appended claims. 125
- What is claimed is:
1. In fire extinguishing apparatus of the character described having a casing provided with a breaking member, a container adapted to contain a liquid and having a body portion and a frangible portion hermetically sealing said body portion, said container being adapted to move by 130 gravity within said apparatus into cooperative relationship with said breaking member for breaking the frangible portion, and a relatively heavy metal member positioned over said frangible portion and attached to the said container, said metal member having an orifice of predetermined restricted size therein through which said liquid is adapted to discharge after breaking of said frangible portion, said metal member serving as a weight to augment the movement of 135 the container and as a metering member to effect a controlled limiting of the rate of discharge of liquid from the container. 140
2. A fire extinguisher of the character described, comprising an outer container for receiving a fire extinguishing liquid, an inner con- 145
- tainer supported within said extinguisher and adapted to contain a second liquid for reaction with said first mentioned liquid to generate an expelling gas, said inner container having a frangible portion hermetically sealing the same, a member positioned over said frangible portion and attached to the inner container, said member having an orifice of predetermined restricted size through which the liquid within the inner container is adapted to discharge after breaking of said frangible portion, and means for breaking the frangible portion of the inner container whereby the restricted orifice of said member then effects a controlled limiting of the rate of discharge of liquid from the inner container. 150
3. A fire extinguisher of the character described, comprising an outer container for receiving a fire extinguishing liquid, an inner container supported within said extinguisher and adapted to contain a second liquid for reaction with said first mentioned liquid to generate an expelling gas, said inner container having a frangible portion hermetically sealing the same, a metal member overlying said frangible portion and attached to said inner container, said metal member having an orifice of predetermined restricted size through which the liquid within the inner container is adapted to discharge, after breaking of said frangible portion, and a breaking and feed controlling projection adapted to enter within said restricted orifice to break the frangible portion of the inner container and then control the discharge of liquid from said inner container, the size of said breaking projection being coordinated with the size of the orifice to effect a controlled limiting of the flow of liquid from the inner container to give a predetermined rate of discharge. 155
4. A fire extinguisher of the character described, comprising an outer container for receiving a fire extinguishing liquid, a tube supported within said outer container, the lower end of said tube being closed and the upper end being in communication with the space within said outer container, an inner container slidably supported within said tube and adapted to contain a second liquid for reaction with said first mentioned liquid to generate an expelling gas, said inner container having a frangible end portion hermetically sealing the same, a metal member overlying said frangible end portion and attached to the inner container, said metal member having a metering orifice of predetermined restricted size in alignment with said frangible portion, a breaking and feed controlling projection mounted in alignment with said inner container and metering orifice and adapted to enter said metering orifice to break the frangible portion of said inner container, the construction being such that upon inversion of the extinguisher and breaking of said frangible portion the inner container slides down about the breaking and feed controlling projection, the size of said projection being coordinated with the size of said metering orifice to then effect controlled limiting of the flow of liquid from the inner container to give a predetermined rate of discharge. 160
5. In fire extinguishing apparatus of the character described, a container adapted to contain a liquid and having a frangible closure hermetically sealing the same, and a metering member having a discharge orifice through which the liquid is adapted to discharge after breaking of said frangible closure, said metering member surrounding said frangible closure and being cemented to said container. 165

6. In fire extinguishing apparatus of the character described, a container adapted to contain a liquid and having a neck portion provided with a frangible closure hermetically sealing the same, and a metal metering member having a depending skirt surrounding said neck portion and cemented thereto, said metering member having an inturned portion above the frangible closure providing an orifice of predetermined size through which the liquid is adapted to discharge after breaking of said frangible closure. 10
7. In fire extinguishing apparatus of the character described, an acid bottle adapted to contain an acid and having a neck portion provided with a frangible closure hermetically sealing the same, and a metal metering member having a depending skirt surrounding said neck portion and cemented thereto, said metering member having an inturned portion above the frangible closure forming an orifice of predetermined size, through which the liquid is adapted to discharge after 20
